UNITED STATES PATENT OFFICE.

GEORGE C. KIMMEL, OF WORCESTER, MASSACHUSETTS, ASSIGNOR, BY MESNE ASSIGNMENTS, TO CINCINNATI GRINDERS INCORPORATED, OF CINCINNATI, OHIO, A CORPORATION OF OHIO.

AUTOMATIC COOLANT-ARRESTING MECHANISM.

Original application filed May 6, 1921, Serial No. 467,297. Divided and this application filed November 20, 1923. Serial No. 675,910.

This invention relates to machine tools and more particularly to the means for controlling the flow of the coolant in grinding machines such as is disclosed in my Patent 5 No. 1,522,465 granted on co-pending application Serial Number 467,297, filed May 6, 1921, of which this application is a division.

In machines of this character, grinding is generally effected by means of a grinder carried on a rapidly revolving spindle mounted in a tool-head and the work and spindle are translated relatively to one another in order to effect the grinding operation, while at the same time the work in the head-stock may 15 be revolved, and in some machines as in the embodiment of my invention to be described it is the grinder which partakes of the translating motion.

To prevent undue heating of the work it 20 is essential that a suitable coolant be constantly applied to the tool and work during the grinding operation.

In machines of this character wherein the article worked upon is frequently changed, 25 and especially in precision work where it is necessary to frequently calibrate the article operated upon, it is necessary to safeguard the operative against injury from contact with the rapidly revolving grinder and other 30 moving parts of the machine. It is also highly desirable that the flow of coolant be arrested during the calibrating operation and change of work, as a continued flow thereof hinders the action of the operator. 35 This invention therefore has for an object to provide, in a machine of this character, that is one in which both the work and tool are rotated and the tool is translated during the grinding operation and is adapted to be 40 moved to an abnormal position, automatically acting means actuated by the abnormal movement of the tool to simultaneously therewith shut off the flow of the coolant.

Other objects and advantages will be in 45 part indicated in the following description and in part rendered apparent therefrom in connection with the annexed drawings.

To enable others skilled in the art so fully 50 to apprehend the underlying features hereof that they may embody the same in the various ways contemplated by this invention, drawings depicting a preferred typical

construction have been annexed as a part of this disclosure and, in such drawings, like characters of reference denote corresponding parts throughout all the views, of which:—

Fig. 1 is a plan of a grinding machine embodying my invention. Fig. 2 is a rear side view thereof, a portion of the sidewall 60 being broken away to disclose interior mechanism and certain hidden parts being shown in dotted lines. Fig. 3 is a plan of the tank for storing the coolant, the pump, valve and controlling mechanisms therefor 65 and Fig. 4 is an end view of Fig. 3.

Inasmuch as this invention relates particularly to the means for rotating and translating the tool relatively to the work and the means for controlling the flow of the 70 coolant, only such parts are described in detail as are deemed necessary for an understanding of the invention. For the sake of convenience the reference characters used herein are the same as those denoting like 75 parts in the parent application Serial No. 467,297, Patent No. 1,522,465 to which reference may be had for a complete understanding of the machine in which the present invention has been embodied.

Referring more particularly to the drawings the invention is disclosed as embodied in a grinding machine comprising a base or housing 1 enclosing and supporting operating devices for a grinding mechanism 85 mounted on the upper face of the housing. The grinding mechanism proper comprises a tool-head 5 and a head-stock 6. The head-stock is mounted on a carriage 7 slidable upon transverse ways 8 and 9 on one end of the housing, and the head-stock may be translated either by means of a hand-wheel 10 having a shaft 11 provided with a suitable feed screw or by the conventional pawl and ratchet feed operated by a rod 12 connected with a reversing mechanism 13 for the tool carriage. The head stock is carried on a rotatable plate 14 adapted to be adjusted by means of a hand-wheel 15 to align the head-stock spindle 16 parallel with the longitudinal axis of the machine for straight grinding, or at an angle thereto for taper grinding. Within a housing in the head-stock enclosed by a cover 17 is a pulley 18

for the spindle 16 having a drive belt 19 entrained thereon.

A tool carriage 20 slides upon suitable ways (not shown) parallel to the longitudinal axis of the machine and rotatably mounted thereon is the tool-stock 5. Secured to the tail end of the tool-head as by means of bolts 38 is a projecting arm 41 carrying at its extreme end an anti-friction roller 42 cooperating with a cam plate 43 carried on a cam block 44 slidably secured in a guideway 45 in the housing by means of a bolt 46 in order to adjust the rearward limit of movement of the tool-head.

15 It will now be understood that as the tool carriage is retracted a sufficient distance from work-engaging position the roller 42 engages the cam-plate 43, and upon continued movement of the tool carriage the cam effects a swinging movement of the tool head to thereby swing the grinder out of the operative's way should he desire to reach over the machine to adjust the work in the chuck. Upon tool advancing movement of 20 the carriage a weight 47, slidable on a bar 48 rigidly secured to the housing and having a connecting cable 49 secured to the tool-head, serves to restore the tool-head to its normal operating position, a pulley 50 on 25 the housing and another pulley 51 on the carriage being provided to properly guide the cable. The return limit of swinging movement of the toolstock is determined by a pin 52 mounted on the tool head engaging 30 a second pin 53, which may be adjustable if desired, mounted in an abutment 54 fixed to the tool carriage.

Within the tool-head is journaled a suitable spindle upon the opposite ends of which 40 are secured the grinding wheel 55, and the pulley 74 (shown in dotted lines only, Fig. 2) over which latter is trained a belt 88 that extends downwardly within the housing and engages a drum 95 mounted upon 45 a jack shaft 96 journaled in the housing. The drum 95 is rather long, and may be made, in sections if so desired, to permit the belt 88 to travel therealong and be driven thereby as the tool carriage is moved 50 back and forth.

Intermediate the pulley 74 and the drum 95 is a stationary idler 90 and a floating idler 91 about which the belt 88 is trained. These idlers act to maintain the proper tension on the belt and permit it to lengthen out as the tool head is swung through the arc of a circle in a retractile movement thereof and to permit the belt to accommodate itself to different belt center distances 55 when using different sizes of wheel spindle pulleys. The shaft 96 is driven, through suitable connections (not shown), from a power driven shaft 108 journaled in suitable bearings at the rear of the housing.

65 The tool carriage may be shifted back and

forth by means of a hand-wheel 117 which has a shaft provided with a pinion engaging a suitable rack on the tool carriage as is fully disclosed in Patent 1,337,139 granted to me April 13, 1920. Means are provided 70 for automatically moving the carriage back and forth which means may be thrown in and out by the clutch lever 119, the reversing of the carriage being accomplished by means of two dogs 120 and 121 adjustably 75 mounted on the tool carriage engaging a reversing lever 122. It should be understood that in ordinary operation of the tool carriage it does not move back sufficiently to cause a turning movement of the tool-head. When however it is desired to inspect or remove the work, the reversing lever is pulled out of the path of movement of the dog 120 and the driving mechanism will then move the tool carriage sufficiently to 80 cause the tool head to be swung on its carriage, the automatic drive for the carriage including a frictional means adapted to slip when the tool head has been swung to its complete limit of movement against the cam 85 block. It is also to be understood that the clutch lever may be so set as to disengage the automatic carriage shifting mechanism, and the hand-wheel 117 may be operated so as to fully retract the carriage. As the tool 90 carriage driving and reversing mechanism forms no part of my present invention, a detailed description thereof is not given herein.

While the carriage is being fully retracted, and just prior to the turning movement of the tool head, an adjustable dog 123 on the rear of the carriage engages one arm of a forked drag link lever 124 pivotally mounted on a stud 125 said lever being connected with a drag link 126 connected with a clutch operating lever 127 rigidly secured to a shaft 128, the opposite end of the lever 127 engaging a collar 129 mounted on a shaft 130 slideable in a sleeve 131 to which are rigidly secured change speed gears 132, the sleeve being supported in bracket bearings 133. Rotating freely on the sleeve 131 is a pulley 134 having a clutch drum 135 adapted to be clutched in sleeve driven engagement 110 thru the instrumentality of a pin 136 operating a clutch ring and operable by sliding movement of the shaft 130. In Fig. 2 for the sake of clearness I have shown the clutch drum in released position while the tool 120 carriage is just about to shift the shaft 130 for effecting this release; the drag link 126, being shown as parted. Over the pulley 134 is trained the belt 19 which like the belt 88 is trained over a stationary idler 137 and 125 a floating idler 138 in order to permit lengthening of the belt as the head stock carriage is moved back and forth on the ways 8 and 9. It can now be seen that coordinate with the full rearward movement 130

of the tool carriage the dog 123 actuates the drag link lever to so move the shaft 130 as to release the pulley 134 from driving engagement with the gears 132. Upon a forward movement of the tool carriage the dog 123 engages the other arm of the forked lever 124 and starts the rotation of the head stock.

Means are provided to furnish a coolant to the work, this means comprising a pump 145 mounted on the cover plate 146 of a tank 147 into which there projects a sump pipe 148 to conduct the coolant to the pump. The pump is driven from the main drive shaft 108 by means of a belt 149 trained over a pulley on the shaft 108 and over a pulley 150 on the pump shaft. The outlet pipe 151 of the pump is provided with an oscillatory valve 152 connected by means of a link 153 with the lever 127, and into the opposite side of the valve is threaded a pipe 154 to which may be attached a rubber hose 155 leading thru a regulating cock 156 to the hollow spindle within the chuck as will be readily understood by referring to my Patent 1,337,140 granted to me April 13, 1920. With this construction, coordinately with the turning movement of the tool head and the shutting off of the power from the head stock, the valve 152 is shut off to thereby automatically cause the coolant to cease flowing. The tank is mounted on rollers 157 so as to enable ready removal of the same from the machine and the tank is provided with a central boss 158 provided with a hole to embrace a locating stop 159 screwed into the housing in order to properly position the tank with reference to the housing. The forward-end of the tool carriage is provided with a marginal wall 160 terminating in a drain spout 161, and the upper surface slopes toward said drain spout to drain the coolant flowing thereon into a compartment within the housing from which an overflow pipe 163 empties into the settling compartment 164 of the tank 147. The inclined guards 33 and 34 on the ways also assist in draining the coolant back to the tank.

From the foregoing it will be observed that both the work and the tool are rotated and that during the grinding operation the tool is automatically given reciprocatory movements of predetermined extent. The tool is also adapted at certain times to be moved to an abnormal position. This movement to abnormal position automatically and simultaneously swings the tool carriage out of its operative position, causes the tool to cease rotating and arrests the flow of coolant. Likewise when the tool is again moved into operative position to start a new grinding operation the valve 152 is opened and the flow of the coolant is restarted.

Without further analysis, the foregoing will so fully reveal the gist of this invention

that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. In a machine of the class described, a housing, a head stock having work supporting mechanism mounted on said housing, a tool head carrying a tool mounted on a carriage movable to and from said head stock, automatic means for moving said tool head toward and from said head-stock, means for rotating the work, means including a pipe for furnishing a cooling medium to the work, a valve in said pipe, and means rendered effective by abnormal movement of said tool head simultaneously to render said work rotating means ineffective and actuate the valve to cut off the flow of coolant to the work.

2. In a machine of the class described, a housing, a head stock having a rotatable shaft mounted on said housing, a tool head mounted on a carriage movable to and from said head stock, automatic means for giving said tool-head a movement of predetermined extent toward and from said head-stock, means permitting said tool head to be given an abnormal movement away from said head stock, means including a pipe and a valve in the pipe for furnishing a coolant to the work in the head stock, and means operative by abnormal retractile movement of the tool head to effect a stoppage of rotation of the shaft in the head stock and to actuate the valve to shut off the flow of coolant.

3. A grinding-machine combining a housing; a head-stock supported upon said housing; a tool-head translatable mounted on said housing; a coolant tank independent of said housing; means to locate and maintain said tank in a predetermined position adjacent said housing; a pump carried by said tank; piping extending from said tank to the pump and thence to a point adjacent the head-stock to deliver coolant to the work carried thereby; means to actuate said pump, a cut-off valve in said piping; means to give to said tool-head reciprocations of a predetermined length during a grinding operation; a lost-motion connection between said tool-head and said valve whereby the valve is maintained open during normal reciprocation of said tool-head; and means permitting said tool-head to be given an abnormal

4
movement to remove the tool to an inoperative position and to cause said lost-motion connection to close said valve.

4. In a grinding machine, in combination, 5 a housing; a head-stock supported thereby; a work-holder rotatably supported by the head-stock; a tool-head slidably mounted on said housing; a power shaft; a driving connection between the power shaft and the 10 work-holder, said driving connection including a clutch and a clutch-actuating lever; a coolant reservoir; a coolant transmission extending from said reservoir to said head-stock; an oscillating cut-off valve in said 15 transmission; an operative connection between said valve and said clutch actuating lever; means to give to said tool-head reciprocations of a predetermined length on said housing during a grinding operation; means 20 to give to said tool-head an abnormal movement; and a connection between said tool-head and said clutch-actuating lever rendered effective by the abnormal movement of the tool-head to release said clutch and to 25 close said valve, thereby to stop rotation of

the work and discontinue the flow of coolant.

5. A grinding machine combining a housing; a rotatable work-supporting head, supported by said housing; a tool-head translatable mounted on said housing; means to give said tool-head reciprocations of a predetermined length during a grinding operation; means permitting said tool-head to be given an abnormal movement away from said work-head at the end of a grinding operation; a coolant transmission adapted to supply coolant to the work, said transmission including a cut-off valve; valve-controlling mechanism including a lever pivoted to said housing adjacent said translatable tool-head; and a lever-actuating dog carried by said tool-head and maintained in a position wherein it contacts with said lever only when said tool head is given its abnormal movement to discontinue the flow of coolant to the work. 35 40 45

In witness whereof, I hereunto subscribe my name.

GEORGE C. KIMMEL.
